UNITED STATES PATENT OFFICE.

HORACE WOODMAN, OF BIDDEFORD, MAINE.

IMPROVEMENT IN MACHINES FOR CLEANING MACHINE-CARDS.

Specification forming part of Letters Patent No. 27,495, dated March 13, 1860.

To all whom it may concern:

Be it known that I, HORACE WOODMAN, of Biddeford, in the county of York and State of Maine, have invented a new and useful Machine for Cleansing the Top Flat Cards of Carding-Machines; and I hereby declare that the following specification, in connection with the accompanying drawings and references marked thereon, constitute a lucid, clear, and exact description of the construction and use of the same, in referring to the said drawings.

Figure 1 denotes a plan or top view of a carding-machine with my invention applied thereto; Fig. 2, a side elevation; Fig. 3, an opposite side elevation, and Fig 4 a back end elevation of the same.

The nature of my invention has for its object great simplicity, durability, and strength for constantly performing the functions necessary; and it consists, first, in raising, suspending, cleansing, and replacing the top flat cards by incline planes moved within the carding-machine and between the arches and ends of the main cylinder, and the brush-bar placed and operated between these incline planes and over the card-cylinder; second, in the secondary incline planes so connected to the main inclined planes as to elevate themselves, and they in turn elevate the top flat cards when these planes pass from the feed-roll to the doffer, and the secondary incline planes depress themselves and the top flat cards with them in the return movement and bring the cards and brush-bar together for cleansing it after it has cleansed the cards; third, in imparting an intermittent motion to the brush-bar by the arrangement of the notched wheel, pawl, and cam or guide; fourth, in imparting to the incline planes and brush-bar a complete and then a partial movement, to first cleanse all the top flat cards and then one or more and then back and cleanse all again, and so on, to give an increased cleansing to the top flat cards most needing it; fifth, in giving the total and partial movement of the incline planes and brush-bar by means of stud and arm combined with pawl, wheel, and cam; sixth, in so arranging the brush-bar in connection with comb that the latter will cleanse the former at each cleansing it gives the top flat cards.

To enable persons skilled in the art to which my invention appertains to construct and carry out the same, I will describe it, as follows.

All necessary portions of the ordinary carding-machine are shown for the application of my invention, viz: A denotes the frame; B, the arches; C, the top flat cards having card filleting or clothing attached to their under parts in the usual manner. a denotes the pins for guiding and retaining the top flat cards in place; D, the central or main cylinder-shaft, the cylinder not being shown; E, the journal-boxes, in which the shaft D is suspended so as to freely revolve. The other well-known portions of the carding-machine are not shown, they not being necessary in describing my invention. These several parts are well known and in common use, and do not, when taken separately, form any part of my invention.

The projecting ends of the journal-boxes E are turned so as to receive the arms G, which freely turn or swing thereon, and are held in place by rings H and set-screws i. These arms G are bent inward, as seen at I, and pass up between the arches B and the ends of main card-cylinder, (not shown,) and terminate in a double-edged incline plane J, while the lower ends of the inclined edges being regular or irregular, may be moved from the same center as the card-cylinder or otherwise. Each of the arms G extend below the center of boxes E, to receive one end of each of the connecting-rods K for its movement and operation, as will be hereinafter seen.

Between the upper ends of arms G or incline planes J there is fixed firmly a brush-bar, (seen at L, Fig. 1,) the top flats C being broken out to show it, the top of which is supplied with a strip of card filleting or clothing.

The incline planes seen at J are so constructed and so operate in conjunction with the top flat cards by coming in contact with their edges (seen at e) and first raising them by inclines c, and then suspending them on the flat or top portion of these incline planes J, while the brush-bar L and its card comes or passes in effectual contact with the card-teeth on the under side of the top flat cards, which are raised, and thus cleanse them, and

by the continued movement of the arms G the second of the double inclines *g* allows or causes the top flat card first cleansed to drop or recede into its original position on the pins *a* of the arches B, and so on. The arms G, in passing from the feeding end of the carding-machine, must raise each of the top flat cards higher than when the brush-bar and arms G are passing toward the feeding end to be cleansed, in order that no contact of cards and brush-bar may take place in this movement. To effect this, I construct two secondary incline planes. (Seen at M.) In each of these are formed two slots *r*, a portion of each being at right angles with arm G and the other part at an angle of about forty-five degrees with the first part, and through the slots *r* are placed pins *s*, which are secured to main incline planes J on arms G. These pins *s* constitute the stop-motion to planes M, up and down or back and forth, by striking each end of slots *r* for that purpose when the planes M are moved either way by the reversal movement of main incline planes J, and are also to allow of the desired and free movements of these secondary inclines M on the main inclines J, and still retain and stop them thereon.

If the arms G and brush-bar L be moved from the feed end of the carding-machine, the edges *h* of the top flat cards C come in contact with the ends *t* of secondary double-incline planes M, and thus move and raise them (the incline planes M) by the slots *r* following the pins *s* until the level portion of slots *r* arrives on these pins *s*. By this movement the incline planes J are virtually extended upward, as seen at Figs. 2 and 3, so as to effectually lift the top flat cards higher during this movement than in the opposite movement. For cleansing the cards in that case or in the forward movement for cleansing the top flat cards their edges or sides *e* come in contact with ends *w* of secondary incline planes M and push them along and down, they being guided and stopped by means of their slots *r* and pins *s*, so that their top and inclined edges shall be as low as the top of the main inclines J.

A shaft (seen at N) is suspended so as to freely revolve in journal-boxes O, Fig. 4. This shaft may represent the feed-roll shaft, and receive its movements by belt and gear from any movable portion of the carding-machine. To one end of the feed-roll shaft N is secured a balance-wheel A³ and handle B³ and to the other end a crank P, which is connected to comb-crank Q by rod R. The comb-shaft is seen at S suspended by stands C³, and the comb at T connected to shaft S by arms Y, which is for the purpose of cleansing the card on brush-bar L, Fig. 1, by effectual contact with it, and depositing the cotton or waste in trough or screen U, the brush-bar L passing to and remaining near this comb T, to allow it to be so cleansed thereby.

Near the end of shaft N is fixed a pinion V, which meshes into and drives stud-gear W, its stud being seen at D⁴, Fig. 2, and this gear in turn meshes into and drives stud-gear X, turning on stud D³, and which drives gear Y, placed so as to turn both with and on shaft Z, and this shaft is suspended to revolve in journal-boxes A², and has a crank B² fixed to each of its ends, which are connected to each lower end of each of the arms G by rods K, and by which motion is given the arms G; and it is desired to impart alternate motion and rest to these arms G, and consequently to the brush-bar L, and still allow the gear Y to continue its turning or revolutions. To effect this, I place and secure a blank wheel D² on shaft Z, near to the gear Y. The wheel D² has two notches, one cut in each opposite side of its periphery, (seen at n,) and into which a pawl E², connected so as to turn on gear Y, forced down by spring F², and secured to gear Y, and is thereby caused to engage with wheel D² when revolving, and so continue until the brush-bar L, Fig. 1, moves to the front end of the carding-machine. Then the pawl E² is disengaged from wheel D² by coming in contact with the edge of fixed guide G². At the moment the pin or stud H² comes in contact with end of arm I² and reverses the movement of brush-bar L, (and intervening parts,) so that the brush-bar L will travel forward under one, two, or more of the top flat cards until the pin or stud H² passes the end of arm I², after which the pawl E² will again engage with wheel D² and put the shaft Z and brush-bar L into motion to move back to the rear end of the carding-machine, ready to again cleanse the top flat cards by movement and effectual contact of card-teeth on brush-bar L with those on the under side of the top flat cards, and so on *ad infinitum*.

The pin H² may be adjustable in gear W, so as to be moved to or from the center, which will cause a greater or less movement of arm I², and consequently give the double cleansing to any desired number of the top flat cards, as a part of them take the greater part of the waste from the cotton.

The different figures of the drawings indicate four several prominent and different positions my invention assumes, in order to better illustrate its operation—*e. g.*, Fig. 1 shows the brush-bar L at the extreme front movement and all other parts of my invention in corresponding position. Fig. 2 denotes the incline planes J and M, raising the central and highest top flat cards in passing from the front to the back end of the machine, the planes M being in position on planes J to raise the top flat cards so high as not to allow the teeth to touch with the teeth of the brush-bar L, and all other parts in corresponding position. Fig. 3 represents the incline planes J and brush-bar L at their extreme back end position ready to commence cleansing the cards by its reverse or forward

movement, and all other parts in corresponding position. Fig. 4 represents the brush-bar L and the incline planes J at the time the extreme forward position is had for the reversal or double movement of brush-bar L under the first two or three top flat cards for giving them a double cleansing, and represents all other parts in a corresponding position.

Various modifications may be made of my within-described invention without changing or avoiding the principle contained therein; but I have shown what I deem the most effectual mode of carrying it out for the purpose specified.

Having thus described my invention, I will state my claim as follows:

1. Raising, suspending, cleansing, and replacing the top flat cards by incline planes J, moved within the carding-machine and between the arches and the end of the main cylinder, and the brush-bar L, placed, secured to, and operated by and between these incline planes and over the card-cylinder, essentially in the manner and for the purposes fully set forth.

2. The secondary incline planes M, so constructed and connected to the main incline planes J as to elevate themselves by contact with top flat cards, and they in turn elevate the top flat cards when these incline planes M pass from the feed-roll toward the doffer, and they being depressed by contact with,

and also the top flat cards with them, in the return movement and bring the card-teeth of the cards and brush-bar effectually together for cleansing the cards, essentially in the manner and for the purposes fully set forth.

3. Imparting an intermittent motion to the brush-bar L by the combination and arrangement of the notched wheel D², pawl E², and cam G², in the manner set forth.

4. Imparting to the incline planes J and M a complete and then a partial movement to first cleanse all the top flat cards once, and then one or more the second time, and then back again to give an increased or double cleansing to the top flat cards most needing it, essentially in the manner and for the purposes fully set forth.

5. Imparting first a complete and then a partial movement to the brush-bar L by means of the stud H² and arm I², combined with pawl E², cam or guides G², and wheel D², or any equivalent combination, essentially in the manner set forth.

6. So arranging and operating the brush-bar L, in connection with comb T, that the latter will cleanse the former at each cleansing it gives the top flat cards, essentially in the manner and for the purposes fully set forth.

HORACE WOODMAN.
